COUNTERWEIGHT SYSTEM

Wesley W. Eager, Los Angeles, and Columbus A. Tierney, San Marino, Calif.

Application September 13, 1932, Serial No. 632,943

21 Claims. (Cl. 20—19)

This invention relates to counterweight systems, and has for an object the provision of a highly efficient counterweight system, which is particularly designed for, but not necessarily limited to, use in conjunction with the closure forming the subject matter of our co-pending application Serial No. 620,884, filed July 5, 1932. The present invention is a division in part and in part is an improvement over the subject matter 10 of the said co-pending application.

A more detailed object is the provision of a counterweight system whereby any suitable load, such as a door mounted for swinging movement about a horizontal axis, can effectively be counterbalanced in such a manner that the door will remain without fastening in any position to which it can be moved.

Another object is to provide a counterweight system wherein the weight whereby the load is counterbalanced is carried by a system of mechanical elements so arranged that in moving from one of its extreme positions to the other, the weight traverses a substantially straight path, one advantage of such a construction being that 25 the suspended weight will not be started swinging when raised or lowered, even if moved quite rapidly.

A further object is to provide an improved and simplified type of weight for a counterweight system which comprises a container adapted to be transported and mounted in operative relation to the remainder of the counterweight system when empty and consequently much lighter than when in actual use when it is filled to the proper 30 level with any suitable weighting material. By employing a container of rectangular cross-sectional configuration and of appropriate dimensions, it is especially adapted to receive a plurality of common bricks, which fit nicely therein, and of which the appropriate number may be supplied to aggregate the necessary weight.

Another object is to provide a counterweight system of the general class described in which are employed especially efficient means for connecting the counterweight to the load, so as to prevent as much frictional resistance to the movement of the parts as possible, thereby enhancing the ease with which the device can be operated and increasing the length of time during which it 45 can be used without necessitating repair or replacement of parts.

A further object is to provide a device of the general character described, in the design of which particular attention has been paid to efficiency and ease of operation, simplicity and rug-

gedness of construction, facility of assembly and durability and general serviceability of the assembled mechanism.

The invention possesses other objects and valuable features, some of which, with the foregoing, will be set forth in the following description of the preferred form of our invention. It is to be understood that we do not limit ourselves to the specific disclosure made by the said description, as we may adopt variations of the preferred form 10 within the scope of our invention, as set forth in the claims.

Referring to the drawing:

Figure 1 is a transverse, vertical sectional view taken through a door and showing in side elevation a counterweight system operably associated therewith and constructed in accordance with the principles of our invention.

Figure 2 is a view similar to Figure 1 but showing the door and counterweight system in the 20 opposite extremes of their respective movements.

Figure 3 is a horizontal sectional view, the plane of section being indicated by the line 3—3 of Figure 2, with the direction of view as indicated by the arrows.

Figure 4 is a view in side elevation of a portion of a slightly modified form of our improved counterweight system.

Figure 5 is a view similar to Figure 4, but showing another slightly modified form.

For the purpose of the present disclosure, one embodiment of our improved counterweight system has been illustrated upon Figures 1 to 3 inclusive, as being operatively associated with a door 6 mounted for pivotal movement about the 35 horizontal axis of a bearing or journal 7 in such a manner that when closed the door 6 occupies a vertical position as illustrated upon Figure 2, in closing relation to an opening 8 in a wall or partition 9, and when open occupies a horizontal, 40 overhead position, extending through the opening 8, as illustrated upon Figure 1. Inasmuch as the details of construction and method of mounting of the door 6 form the subject matter 45 of our co-pending application, mentioned hereinabove, suffice it for the purpose of the present disclosure to explain that the means for pivotally mounting the door 6 comprises a plurality of aligned brackets 11 (only one of which is illustrated) rigid with the wall or partition 9, and 50 preferably a similar number of brackets 12, each of which is rigid with the door 6. Each of the stationary brackets 11 comprises a leg 13 inclining upwards and inwards from the wall 9 and another leg 14 inclining downwards and inwards 55

from the wall 9 to intersect the leg 13 and be rigidly joined thereto. Each of the stationary brackets 11 carries one of the journals 7 through which a stub shaft 16 extends, all of these shafts 5 16 being in axial alignment and providing the means for pivotally supporting the door 6. This is accomplished by rigidly fastening as by a nut 17 each of the door brackets 12 to an end of the associated stub shaft 16, as best illustrated upon 10 Figure 3. As is also explained in our previously filed application, reference to which has been made hereinabove, the aligned axes of the stub shafts lie within the plane which also includes the center of gravity of the door 6 and which inclines upwards and inwards at substantially 45° 15 with respect to the plane of the door 6. It should be understood that whereas we have illustrated our improved counterweight system as being operatively associated with a door 6 of the type forming the subject matter of our aforesaid co-pending application, we do not wish to be limited to such use of our counterweight system, inasmuch as it is adaptable to various other types of closures and, indeed, in a great many installations where it is desirable to provide an efficient counterweight for practically any type of load.

As many of the improved counterweight systems as may be desirable or necessary are employed with each door or closure 6. However, 30 inasmuch as all those employed with each door are of identical construction, it will be sufficient to describe but one of them. This counterweight system which is indicated in its entirety at 21 is connected to its load (i. e., the door 6) through 35 the expedient of an arm 22 which is rigidly connected as by a nut 23 to the end of the stub shaft 16 opposite that to which the associated door bracket 12 is connected. This is an important detail of construction of our device inasmuch as 40 it distributes the force applied by the counterweight system 21 and the force applied by the door 6 upon opposite sides of the journal 7, thereby preventing the twisting effect upon the bracket 11 carrying the journal 7 which would be applied thereto were both these forces applied at the same 45 end of the journal 7. This assists in holding all the said shafts 16 accurately in coaxial alignment and thus reduces to an absolute minimum the frictional resistance to motion of the stub shafts 50 16 within their respective journals 7.

The arm 22 is pivotally connected as by a pin 26 to a lever 27; and from one end 28 of the lever 27 a counterweight 29 is suspended, as will readily be understood from observation of Figures 1 and 2. As is also explained in application Serial No. 620,884, of which this application is a division in part, the axis of the pin 26 whereby the force of the counterweight 29 is applied to the arm 22, also lies within the plane which includes the axes 55 of the stub shafts and the center of gravity of the door 6. Hence the respective turning moments of the door 6 and of the counterweight 29 about the axes of the stub shafts are always equal to each other, regardless of the position to which 60 the door is moved. The result of this feature is that the counterweight system is able to sustain the door motionless in any position to which the door can be moved, without the necessity of fastening the door in that position. These figures 65 show that when the door swings from closed position (Figure 2) to open position (Figure 1), the arm 22 swings downwards through 90° of rotation about the axis of the journal 7, carrying with it the pin 26 which is connected to the 70 mid-portion of the lever 27. As the pin 26 moves

downwards, the lever 27 swings in clockwise direction about the axis of a pin 32 whereby a roller 33 is journaled on the other end 30 of the lever 27, and the pin 31 whereby the weight 29 is pivotally connected to the lever 27 will also move downwards but through twice the distance traversed by the pin 26. Thus, it may be seen that the moment of the force exerted by the counterweight 29 is equal to the weight of the counterweight 29 multiplied by the distance between the pins 26 and 31 plus the distance between the pin 26 and the stub shaft 16. Inasmuch as the arm 22 will have to be longer than the distance between the axis of the shaft 16 and the axis of the pin 26 in order to make it possible to secure 15 both the pin 26 and the shaft 16 rigidly to the arm, the distance between these axes will be termed "the effective length of the arm 22" throughout the remainder of this specification and the claims. Similarly, the effective length 20 of the end 28 of the lever 27 will be considered as designating the distance between the axes of the pins 31 and 26; and the effective length of the end 30 of the lever 27 will be considered to indicate the distance between the axis of the pin 25 26 and the pin 32. The distance between the axes of the pins 26 and 32 is equal to the distance between the axes of the pins 26 and 31, i. e., the effective length of the end 30 of the lever is equal to the effective length 23 thereof; and each of 30 these distances is equal to the effective length of the arm 22.

Inasmuch as the axes of the shaft 17 and the pin 32 about which the arm 22 and lever 27, respectively, turn, are spaced apart and since 35 the arm 22 and lever 27 are interconnected by the pin 26, it is necessary to compensate for their arcuate movements in opposite directions in order to permit freedom of movement of the members. In the modification illustrated, this is accomplished by permitting the pin 32 to vary its distance from the shaft 17, preferably by movement in a horizontal path. Accordingly, means are provided for guiding the roller 33 for movement with its axis in the horizontal plane which 40 includes the axis of the journal 7. In this manner, a moving fulcrum for the lever 27 is provided. This guiding means comprises a track 36 45 preferably in the form of an angle iron which may conveniently be a horizontal extension of 50 either of the legs 13 or 14, say the leg 13 of the stationary bracket 11. The roller 33 is disposed in rolling engagement with the track 36; and the parts are so proportioned and arranged that the axis of the pin 32 is disposed in parallelism 55 with and in horizontal alignment with the axis of the journal 7.

Owing to the equality of the effective lengths of the arm 22 and the ends 28 and 30 of the lever 27, the pin 31 whereupon the counterweight 29 is 60 suspended, will traverse a perfectly straight, vertical path in moving from one extreme of its motion to the other. This follows from the fact that even though both the arm 22 and the end 28 of the lever swing about their respective axes 65 in rotary motion, their respective projected lengths in a horizontal plane are equal, the result being that throughout the entire range of movement of the device both the pin 31 and the shaft 16 are disposed with their axes in a common 70 vertical plane. This is an important detail inasmuch as it prevents the counterweight 29 from being started swinging even though it is moved from one extreme of its vertical movement to the other relatively rapidly. This type of 75

- movement of the lever 27 which permits the pin 31 to move in a truly vertical path is made possible by the moving fulcrum for the lever 27 which is provided by the roller 33 and track 36.
- 5 As the arm 22 swings downwards from the position illustrated upon Figure 2 toward that position in which it extends horizontally, the entire lever 27 swings in clockwise rotation with the end 30 moving inwards away from the wall 9, and
- 10 after the horizontal position of the arm 22 has been passed, these parts move back toward the wall 9. These movements of the lever 27 occur in reverse order as the counterweight 29 is being raised, i. e. while the door is being closed; and
- 15 the consequent motion of the pin 32 carried by the end 30 of the lever 27 toward and away from the axis of the bearing 7 is made possible because of the rolling engagement of the roller 33 upon the track 36.
- 20 Figure 4 shows a slightly modified form of device for providing this moving fulcrum. Here the lower leg 13' of the stationary bracket 11', instead of being bent to horizontality, is continued straight on beyond the journal 7' and has a link 25 41 pivoted to its upper end as by a pin 42. The lever 27' upon which the counterweight (not shown) is suspended is pivoted intermediate its ends to the arm 22' which is rigid with the load (not shown) and which is constructed similarly
- 30 to the arm 22 of the previously described modification. The end 30' of the lever 27' which is opposite the end 28' from which the counterweight is suspended is pivoted to the link 41 as by a pin 43. Hence, the link 41 is continually 35 in compression, it being understood that the counterweight tends to make the lever 27' rotate in a clockwise direction about the pin 26' whereby the lever 27' is pivoted to the arm 22'. The link 41 is enabled to swing from the full line 40 position shown upon Figure 4 to the dotted line position, thereby permitting the shifting of the pin 43 which is analogous to the horizontal movement of the pin 42 whereupon the roller 33 is journaled. It should be explained, however, that 45 in this modification, owing to the slight deviation of the pin 43 from truly horizontal movement, the movement of the counterweight is not as accurately in a straight vertical line as in the case of the previously described modification.
- 50 Figure 5 shows still another modified form which is identical with that illustrated upon Figure 4, with the exception that it is the upper leg 14'' instead of the lower leg 13'' of the stationary bracket 11'' which is extended to provide the 55 stationary support for the link 46 to which the after end 30'' of the lever 27'' is pivoted. In this modification the link 46 is continually under tension.
- Another advantage gained as a result of using 60 the construction hereinabove described is that the lever 27 never moves to vertical position. In the lowermost position of the counterweight, the lever inclines downwards from the pin 32 at substantially 45°, and as the counterweight moves 65 upwards, the lever 27 swings upwards until it inclines upwards from the pin 32 at substantially 45°. Hence, the lever 27 is always inclined at least substantially 45° from the vertical, the result being that the turning moment of the counterweight, as well as that of the door 6, is always 70 in excess of zero. The importance of this is that at least a portion of the forces exerted by the counterweight and the door are exerted directly against each other at all times, thereby taking up all lost motion, and the parts cannot be swung

to a position wherein any looseness in the bearings or other parts will permit the door to move even slightly without a corresponding movement of the counterweight.

The construction of the counterweight 29 is 5 another important detail of our invention. Although the entire counterweight system would operate with equal efficiency with any type of suitable weight, we prefer to employ a hollow container 51 suspended in a suitable hanger 52 from 10 the pin 31. This container 51 is of rectangular cross-sectional configuration, as clearly shown upon Figure 3 and is adapted to be transported empty and, consequently, relatively light. However, after its installation in operative position, 15 it should be filled with any suitable weighting material, such, for example, as a plurality of common brick 53, the proper number being utilized so that they aggregate the necessary weight to insure satisfactory counterbalancing of the weight 20 of the door 6, or whatever load is applied to the device.

We claim:

1. In combination, a closure, pivot means supporting said closure, a counterweight, and means 25 interconnecting said closure and said counterweight whereby their respective turning moments about said pivot means are equal to each other in all positions of said closure.

2. In combination, a closure, pivot means supporting said closure for movement about a horizontal axis, a counterweight, and means interconnecting said closure and said counterweight whereby their respective turning moments about 30 said pivot means are equal to each other in all 35 positions of said closure.

3. In combination, a closure, pivot means supporting said closure for movement about a horizontal axis and supporting the entire weight of 40 said closure in all positions thereof, a counterweight, and means interconnecting said closure and said counterweight whereby their respective turning moments about said pivot means are equal to each other in all 45 positions of said closure.

4. In combination, a closure, pivot means supporting said closure for movement about a horizontal axis, and means for releasably retaining 50 said closure in any position to which it can be moved comprising a counterweight and means operatively connecting said counterweight to said closure and supporting said counterweight for movement proportionally with the movement of said closure and in a substantially straight line.

5. A counterweight system for balancing a predetermined load mounted upon a supporting 55 structure for movement about a given axis, comprising an arm rigid with said load and extending beyond said axis therefrom, a lever pivoted between its ends to said arm, a weight carried by one end of said lever, and means movably connecting the other end of said lever to said supporting structure.

6. A counterweight system for balancing a predetermined load mounted upon a supporting structure for movement about a given axis, comprising 65 an arm rigid with said load and extending beyond said axis therefrom, a lever pivoted between its ends to said arm, a weight carried by one end of said lever, and means connecting the other end of said lever to said supporting structure and for guiding said other end in movement substantially in a plane including said axis.

7. A counterweight system for balancing a predetermined load mounted upon a supporting structure for movement about a given axis, com- 75

- prising an arm rigid with said load and extending beyond said axis therefrom, a lever pivoted between its ends to said arm, a weight carried by one end of said lever, and means connecting the other end of said lever to said supporting structure and for guiding said other end toward and away from said axis.
8. A counterweight system for balancing a predetermined load mounted upon a supporting structure for movement about a given axis, comprising an arm rigid with said load and extending beyond said axis therefrom, a lever pivoted between its ends to said arm, a weight carried by one end of said lever, and means connecting the other end of said lever to said supporting structure and for guiding said other end, and means providing a movable fulcrum for the other end of said lever.
9. A counterweight system for balancing a predetermined load mounted upon a supporting structure for movement about a horizontal axis, comprising an arm connected to said load and extending beyond said axis therefrom, a lever pivoted between its ends to said arm, a weight carried by one end of said lever, and means movably retaining the other end of said lever substantially within the horizontal plane of said axis.
10. A counterweight system for balancing a predetermined load mounted upon a supporting structure for movement about a horizontal axis, comprising an arm connected to said load and extending beyond said axis therefrom, a lever pivoted between its ends to said arm, a weight carried by one end of said lever, a roller journaled upon the other end of said lever, and a track rigid with said supporting structure and guiding said roller in movement toward and away from said axis.
11. A counterweight system for balancing a predetermined load mounted upon a supporting structure for movement about a horizontal axis, comprising an arm connected to said load and extending beyond said axis therefrom, a lever pivoted between its ends to said arm, a weight carried by one end of said lever, a roller journaled upon the other end of said lever, and a track rigid with said supporting structure and guiding said roller for movement with the axis thereof substantially within the horizontal plane including the axis of movement of said load.
12. A counterweight system for balancing a predetermined load mounted upon a supporting structure for movement about a horizontal axis, comprising an arm connected to said load and extending beyond said axis therefrom, a lever pivoted between its ends to said arm, a weight carried by one end of said lever, a track rigid with said supporting structure, and means on the other end of said lever guided by said track in movement toward and away from said axis.
13. A counterweight system for balancing a predetermined load mounted upon a supporting structure for movement about a horizontal axis, comprising an arm connected to said load and extending beyond said axis therefrom, a lever pivoted between its ends to said arm, a weight carried by one end of said lever, and means movably retaining the other end of said lever substantially within the horizontal plane of said axis, the effective length of each end of said lever and the effective length of said arm from said axis to said lever being equal.
14. A counterweight system for balancing a predetermined load mounted upon a supporting structure for movement about a horizontal axis,
- comprising an arm connected to said load and extending beyond said axis therefrom, a lever pivoted between its ends to said arm, a weight carried by one end of said lever, a roller journaled upon the other end of said lever, and a track rigid with said supporting structure and guiding said roller for movement with the axis thereof substantially within the horizontal plane including the axis of movement of said load, the effective length of each end of said lever and the effective length of said arm from said axis of movement of said load to said lever being equal.
15. A counterweight system for balancing a predetermined load mounted upon a supporting structure for movement about a horizontal axis, comprising an arm connected to said load and extending beyond said axis therefrom, a lever pivoted between its ends to said arm, a weight carried by one end of said lever, a link pivoted at one end to said supporting structure and at its other end to the other end of said lever to retain said other end of said lever substantially within the horizontal plane of said axis, the effective length of each end of said lever and the effective length of said arm from said axis to said lever being equal.
16. In a counterweight system for balancing a load, a counterweight, and guiding means therefor comprising a supporting structure, an arm pivotally mounted thereon for movement about a given axis and operably connected to said load, a lever pivoted between its ends to said arm, said counterweight being connected to an end of said lever, and means guiding the other end of said lever for movement toward and away from said axis.
17. In a counterbalancing device for a load pivotally mounted for movement about a horizontal axis, comprising an arm extending from said load beyond said axis of movement thereof, a lever pivoted intermediate its ends to said arm at a point beyond said axis of movement of said load from the load itself, said point, the center of gravity of said load, and said axis of pivotal movement of said load all lying in a common plane, a weight connected to said lever adjacent one end thereof, and means for guiding the other end of said lever in a substantially horizontal path.
18. In a counterbalancing device for a load pivotally mounted upon a supporting structure, an arm extending from said load beyond the axis of pivotal movement thereof, a lever, a counterweight carried by said lever, means connecting said lever to said supporting structure and providing a fulcrum about which said lever is adapted to swing, and means connecting said lever to said arm whereby the arm is caused to swing in arcuate motion opposite to that of the lever, at least one of said connecting means including means for compensating for the arcuate movements of said arm and lever.
19. In a counterbalancing device for a load pivotally mounted upon a supporting structure, an arm extending from said load beyond the axis of pivotal movement thereof, a lever, a counterweight carried by said lever, means connecting said lever to said supporting structure and providing a fulcrum about which said lever is adapted to swing, and means connecting said lever to said arm whereby the arm is caused to swing in arcuate motion opposite to that of the lever, at least one of said connecting means being movable with respect to one of the members interconnected thereby to compensate for the arcuate movements of said arm and lever.

20. In combination, a closure, pivot means supporting said closure, a counterweight and means interconnecting said closure and said counterweight whereby their respective turning moments about said pivot means are always in excess of zero and are equal to each other in all positions of said closure.

21. In combination, a closure, pivot means sup-

porting said closure, a counterweight and means interconnecting said closure and said counterweight whereby their respective turning moments about said pivot means are always in excess of zero and whereby the ratio between said turning moments is maintained substantially constant. 5
